UNITED STATES PATENT OFFICE.

AUGUSTE SCHEUCHZER, OF RENEUS, NEAR LAUSANNE, SWITZERLAND, ASSIGNOR TO FERRODESHERBEUSE SCHEUCHZER SOCIETE ANONYME, OF RENEUS, SWITZERLAND.

MACHINE FOR REMOVING WEEDS FROM RAILWAY ROADBEDS.

Application filed April 19, 1922. Serial No. 555,553.

To all whom it may concern:

Be it known that I, AUGUSTE SCHEUCHZER, a citizen of the Republic of Switzerland, residing at Reneus, near Lausanne, Switzerland, have invented certain new and useful Improvements in Machines for Removing Weeds from Railway Roadbeds, of which the following is a specification.

The present invention relates to a machine for removing weeds from railway road beds. This machine is provided like my copending application filed April 28th, 1921, Ser. No. 465,272 with knives which are moved into and out of the ballast by means 15 of an auxiliary motor automatically actuated by members which contact with certain parts of the road bed.

The present invention has the same general objects as those described in my copending application, with the addition of means for limiting the stroke of the knives into the ballast. The main feature of this improved form of machine is a slidable and rotatable sleeve on the rod which is moved longitudinally by the auxiliary motor. One edge of this sleeve is provided with notches preferably arranged in two opposed sets with which coat projections for teeth on a slidable non-rotating sleeve which is also mounted on the longitudinally movable rod for regulating the stroke or raising action of the knives. The freely rotatable sleeve has associated therewith a lever arrangement which is operable by the driver and in order to reduce the possibility of accidents to a minimum this lever device is connected with the tie engaging means which controls the operation of the motor driven knife means for ensuring of an automatic operation of the machine especially when engaging obstacles on a road bed positioned above a predetermined fixed lever. As a result of this improved arrangement at each road crossing, that is, where the road is level with the rails the stroke of the knives is so adjusted that the knives will not reach the ground.

The invention is clearly illustrated in the accompanying drawings, in which:—

Fig. 1 is a side elevational view of the improved machine, the parts being arranged in the position in which the knives are permitted their shortest stroke,

Fig. 2 is an enlarged extended plan de-

tail of the slidable and rotatable sleeve, as well as the sliding sleeve, and

Fig. 3 is an enlarged transverse sectional detail of the rotatable and slidable sleeve.

Similar characters of reference are employed in all of the above described views, to indicate corresponding parts.

Referring now, more particularly, to the accompanying drawings the knives 15 oscillate about the axis 151 located upon a support which is adapted to travel along the road bed and these knives are driven into the ballast by means of the pivotally mounted bell crank lever 150. One arm of the lever is connected to the piston rod 153 of the steam cylinder; the other arm of the lever has connected thereto one end of a connecting rod 152, the opposite end of which is associated with knives 15. Pivoted to and extending longitudinally and rearwardly from the rod 152 and slidable in bearings 155 mounted in turn on the support is another rod 154. A spiral spring 156 is disposed about the rod 154 and has one end thereof bearing against the collar 158 which is positioned in proximity to the rear bearing 155. A sleeve 170 is slidably and rotatably mounted on the rod adjacent the forward bearing 155. The rear edge of this sleeve 170 is provided with notches arranged in stepped formation or preferably in opposed pairs with each pair of varying depth. Another sleeve 157 is also slidably mounted on the rod 154 and is provided on one edge with longitudinally extending and diametrically opposite projections or stops of the same width as the notches in the sleeve 170 for coacting therewith in limiting the stroke of the longitudinal rods 153 and 154 and consequently the knives 15. The coacting engagement of the projections with either of the sets of notches is effected according to the position of the turnable sleeve 170 on the rod 154. This sleeve 170 is also connected to one arm of a bell crank lever 181 by means of an adjustable rod 182 while the other arm of the bell crank lever 181 is slidably connected with a link the opposite end of which is pivoted to the lower end of a hand operated lever 180. By means of this lever 180 preferably operated by the engine driver it is possible to adjust the angular position of the sleeve on the rod 154. One of the arms of the bell crank

lever 181 is also connected as at 160 with the connecting rod 161, the connection 160 being adapted to operate in a slotted link, while the other extremity of the rod 161 is connected to an arm 163 which oscillates about the axis 151 and carries on its outer extremity the road bed and tie engaging roller 162. In this connection it may also be noted that a valve operating gear generally designated 164 is associated with the arm 163 for controlling the actuation of the valve 165 for the steam cylinder 166 which actuates the piston rod 163 in a manner substantially in accordance with the 15 operation of the cylinder in my copending application previously mentioned. The adjustment of the stroke of the knives is effected by means of the coaction between the notches and the sleeve 170 and the projections of the sleeve 157. When the sleeve 170 is partially rotated on a rod 154 one of the other sets of notches are in position to be contacted by the projections on the sleeve 157. When the parts are in the position 20 shown in Fig. 1 the knives are operated in their shortest stroke. When it is desired to move the parts into an inactive position as when traveling over a road crossing where the bed is level with the rails, the lever 180 is moved in the direction indicated by the arrow causing the inner end of the slotted link to bear against the pivot point 160 to consequently rock the bell crank lever 181 and by reason of connection of the 25 adjustable rod 182 between this bell crank lever and the sleeve 154 the latter is turned so that the unnotched or free edged portions 170' of the sleeve 170 will abut or contact with the projections on the sleeve 159 and 30 as a result so limit the stroke of the knives 15 that they will not engage the road bed. When an obstacle projects above the bed so that effective working of the parts are 35 endangered such obstacle is engaged by the 40 roller 162 and causes the arm 163 to turn anti-clockwise. This action automatically effects an adjustment or turning of the bell crank lever 181 and the sleeve 170 and consequently arranges the sleeves in such 45 a position that the stroke of the knives will be such that they will not contact with the 50 obstacle.

Having thus fully described the invention what is claimed as new and desired to be secured by Letters Patent is:—

1. A machine of the character described comprising a support adapted to traverse a railway track, a knife carried by said support, motor actuated means for raising and

lowering said knife, tie engaging means controlling the motor driven means for automatically lifting the knife over the ties and means for regulating the knife raising action of the motor actuated means. 60

2. A machine of the character described comprising a support adapted to traverse a railway track, a knife carried by said support, motor actuated means for raising and lowering said knife, tie engaging means controlling the motor driven means for automatically lifting the knife over the ties and means including a reciprocal member for regulating the knife raising action of the motor actuated means. 65 70

3. A machine of the character described comprising a support adapted to traverse railway tracks, a ground engaging knife, motor actuated means for raising and lowering said knife, tie engaging means associated with the knife for controlling the motor driven means for automatically lifting the knife over the tie, and means for regulating the knife raising action of the motor actuating means including a member connected to the motor actuating means and reciprocal in the support, coacting stops mounted on the member and an operable connection between one of said stops and the tie engaging means for partially rotating said stop, substantially as and for the 80 85 purpose set forth. 90

4. A machine as claimed in claim 3 wherein one of the stops is slidably mounted on the member and is provided with opposed projections while the other stop is turnably mounted on the member and is formed in its edge adjacent the projections with series of notches of variable depths. 95

5. A machine as claimed in claim 3 wherein a manually operable lever is pivotally mounted on the support and operably connected with the operable connection between the turnable sleeve and the tie engaging means, substantially as and for the purposes set forth. 100

6. A machine as claimed in claim 3 wherein the operable connection between the turnable sleeve and the tie engaging means includes a pivotally mounted bell crank lever, an adjustable rod between one arm of the bell crank lever and the turnable sleeve and a connecting rod between the other arm of the bell crank lever and the tie engaging means. 110

In testimony whereof I hereunto affix my 115 signature.

AUGUSTE SCHEUCHZER.
